UNITED STATES PATENT OFFICE.

DAVID E. EMANUEL, OF DES MOINES, IOWA.

OPERA-CHAIR.

1,180,637.

Specification of Letters Patent. Patented Apr. 25, 1916.

Application filed July 21, 1915. Serial No. 41,186.

To all whom it may concern:

Be it known that I, DAVID E. EMANUEL, a citizen of the United States, and resident of Des Moines, in the county of Polk and State of Iowa, have invented a certain new and useful Opera-Chair, of which the following is a specification.

The object of my invention is to provide an opera chair of simple, durable and inexpensive construction.

A further object is to provide an opera chair of the type having a seat adapted to slide rearwardly to permit persons to pass through the aisle with a minimum of interference and inconvenience.

A further object is to provide an opera chair having a back pivoted near its upper portion and having a seat mounted with relation to said back and adapted to travel into a slot in the back and also having a part pivotally mounted on the back, both of the parts of said seat being capable of pivotal movement with relation to the back when the seat is raised.

My invention consists in the construction, arrangement and combination of the various parts of the device whereby the objects contemplated are attained, as hereinafter more fully set forth pointed out in my claims and illustrated in the accompanying drawings, in which:

Figure 1 shows a front elevation of a chair embodying my invention. Fig. 2 shows a vertical sectional view of the same taken on the line 2-2 of Fig. 1. Fig. 3 shows an enlarged vertical sectional view of the lower part of the back and the rear portion of the seat, taken on the line 3-3 of Fig. 1. Fig. 4 shows a vertical transverse sectional view, taken on the line 4-4 of Fig. 3.

In the accompanying drawings, I have used the reference numeral 10 to indicate generally the lower support of a chair which may be of any desired form, for instance, as that of a pedestal, as shown in my drawings.

On the upper portion of the supporting member 10 are suitable frame members 11. My improved chair has the spaced upwardly extending back members 12, and suitable arm rests 13, which may be of any desired construction.

Pivotedly mounted between the upper ends of the members 12 is a back member 14. The members 12 are inclined from their lower ends upwardly and slightly rear-

wardly at a proper angle to afford convenience to the occupant of the chair.

Mounted upon the frame 11 is a substantially rectangular frame 15 having approximately the form of a sheet of metal or the like, with its central portion cut away. At the side of the frame 15 are upwardly extending members 16, at the upper ends of which are inwardly extending members 17. At the rear outer corners of the frame 15 are upwardly extending ears 18, pivotally connected with the back. Mounted upon the frame 15 is a suitable seat member 19 having in its sides grooves to receive the members 17.

In the forward portion of the frame 11 are rollers 20 on which the frame 15 travels. It will be seen that the seat 19 may slide with relation to the frame 15 and also that the forward end of the frame 15 slides freely on the rollers 20, and that the rearward end of said frame is supported by the back 14 and swings thereon. In this connection it may be mentioned that the rear portion of the seat 19 comprises a plurality of transverse members 21 connected by a flexible strip 22. The lower portion of the back 14 is formed with a slot 23, and the parts are so constructed and arranged that when the seat 19 is in its forward position and is pushed rearwardly, the members 21 will slide upwardly into the slot 23. The back 14 comprises a wooden member covered on front and back by a pair of metal sheets. The wooden member extends to the lower ends of the metal sheets, and a space below the wooden member forms the slot 23.

In the practical operation and use of my improved seat, it will be noted that the seat member 19 projects forwardly beyond the other parts of the seat. Assuming that the seat is not occupied, the seat member 19 and the frame 15 may be tilted upwardly to the position shown by the dotted lines in Fig. 2. When it is desired to occupy the seat, the seat member 19 and frame 15 are swung downwardly to the position shown by the full lines in Fig. 2. Assuming that the occupant of the seat desires to move rearwardly, permitting another person to pass into the aisle in front of the occupied seat, the occupant simply grasps the arms 13 or places his feet on the floor and pushes rearwardly. The seat 19 and the frame 15 move rearwardly, the frame 15 traveling

over the rollers 20 and the back 14 swings rearwardly on its pivot points. On the forward end of the frame 15 is a downwardly projecting member 24 which engages one of 5 the frame members 11 when the back 15 has reached perpendicular position, and thereupon the seat 15 slides rearwardly with relation to the frame 15 and the members 20 slide upwardly into the slot 23. When the 10 rearward movement has been completed, the knees and feet of the occupant of the seat will be withdrawn from the aisle for permitting persons to pass therethrough. The occupant of the seat may easily swing 15 forward again to any comfortable position.

Incidentally it may be noted that one of the advantages of a seat of this kind arises from the fact that the back may be inclined to various angles to suit the convenience of 20 the occupant of the seat.

My improved chair is of comparatively simple construction, and can be manufactured at a small expense.

It will be understood that the chair will 25 be constructed with curved edges, so that with such an arrangement of the parts, there will be no danger of tearing the garments of the user.

It will be understood that some changes 30 may be made in the construction and arrangement of the parts of my improved opera chair without departing from its essential features and purposes, and it is my intention to cover by this application any 35 such changes which may be included within the scope of my claims.

My seat member is made partially col-

lapsible for reducing it to the narrowest width from front to rear, for accommodating passers-by and at the same time affording sufficient room for the occupant. 40

I claim as my invention.

1. In a chair a supporting member having spaced upwardly extending back members, a back pivoted at its upper end to said members, having a slot in its lower end, a seat slidably mounted on said support, having a flexible portion adapted to slide into 45 said slot.

2. In a chair, a supporting member having spaced upwardly extending back members, a back pivoted at its upper end to said members, having a slot in its lower end, a movable frame member secured to the lower part of said back, a seat slidably mounted 50 on said movable frame member having a flexible portion adapted to slide into said slot.

3. In a chair, a supporting member having spaced upwardly extending back members, a back pivoted at its upper end to said members, having a slot in its lower end, a frame member slidably mounted on said support, and pivoted to the lower part of 55 said back, a seat slidably mounted on said frame, said seat and frame being capable of pivotal movement with relation to said back.

Des Moines, Iowa, July 19, 1915.

DAVID E. EMANUEL.
